UNITED STATES PATENT OFFICE

100,909

DESIGN FOR A LACE

Joseph D. Wiener, New York, N. Y.

Application July 23, 1936, Serial No. 64,005

Term of patent 3½ years

To all whom it may concern:

Be it known that I, Joseph D. Wiener, a citizen of the United States of America, residing in the city of New York, county of New York, and State of New York, have invented a new, original and ornamental Design for a Lace, of which the following is a specification, reference being had to the accompanying drawing, forming part thereof.

The figure of the drawing is a plan view of a lace embodying my new design.

The design unit is contained between the broken lines, which unit is repeated in regular succession, as indicated by the extensions beyond the unit boundaries.

I claim:

The ornamental design for a lace substantially as shown and described.

JOSEPH D. WIENER.
